No. 681,197.

Patented Aug. 27, 1901.

W. F. COOPER.
ACETYLENE GAS LAMP.

(Application filed Oct. 27, 1898. Renewed Jan. 21, 1901.)

(No Model.)

UNITED STATES PATENT OFFICE.

WILLIAM FREDRIC COOPER, OF MERIDEN, CONNECTICUT.

ACETYLENE-GAS LAMP.

SPECIFICATION forming part of Letters Patent No. 681,197, dated August 27, 1901.

Application filed October 27, 1898. Renewed January 21, 1901. Serial No. 44,157. (No model.)

To all whom it may concern:

Be it known that I, WILLIAM FREDRIC COOPER, of Meriden, in the county of New Haven and State of Connecticut, have invented a new and Improved Acetylene Lamp and Generator, of which the following is a full, clear, and exact description.

My invention relates to an improvement in acetylene lamps or lanterns, and comprises the novel features hereinafter described and claimed.

Reference is to be had to the accompanying drawings, forming a part of this specification, in which similar characters of reference indicate corresponding parts in all the views.

Figure 1 is a sectional elevation of my device. Fig. 2 is a cross-section taken upon the line 2 2 of Fig. 1. Fig. 3 is a detail sectional elevation showing the valve and adjacent parts in a different position from that shown in Fig. 1. Fig. 4 is a perspective view showing the valve and its stem; and Fig. 5 is a detail sectional elevation through the dry-ing-chamber, showing a burner attached.

The object of my invention is to provide a practical and simple lamp or lantern using acetylene gas for lighting, having more particularly in view the adaptation of the device for use upon bicycles.

In my lamp or lantern the variation in volume of the gas-chamber is provided for by having a portion of the wall thereof constructed of a flexible material and having the same compressed by means of a spring. At the base of the lamp or lantern is a chamber A, adapted to contain water and provided with a cap a, by means of which the contents may be renewed or discharged. At the upper end of this chamber and at some distance above the level of the water is a conical flange C, secured at its outer edges to the walls of the chamber and extending downwardly and toward the center. The apex of this cone is removed, leaving a passage connecting with the upper side of the flange.

To the walls of the chamber, at the upper edge of the flange C, is connected the expanding member D, which consists of leather, rubber, or any suitable material which is adapted to answer as the flexible wall of a

bellows. The upper edge of this bellows is connected with the lower portion of the chamber B, which is the carbid-holder. The bottom B' of this chamber is of conical shape, corresponding substantially with the shape 55 of the flange C. The opening at the apex of the cone forming the bottom B' is smaller than that in the flange C. This opening is normally closed by a valve E, which is within the carbid-holder and seats over the opening. 60 The valve E has a stem E' extending downwardly, to the lower end of which is secured a pair of cross-arms E², adapted to engage the upper surface of the conical flange C. The carbid L is placed within chamber B in powdered form, and will thus pass through the opening in the bottom and drop into the water when the valve E is raised.

The valve E may be locked down, so that it may not be raised, by a rod G, which is threaded at its upper end and extends through a threaded hole in the top of the carbid-holder. This rod is provided with a knob G', by means of which it may be readily adjusted. A spiral spring e surrounds the stem of the valve, 70 bearing at its lower end against the cross-bars E² and at its upper end against the bottom of the carbid-holder. This spring e serves to hold the valve closed. A second spring F, which is considerably stronger than the spring 75 e, lies between the upper surface of the conical flange C and the lower surface of the conical bottom of the carbid-holder. This spring is attached to the flange and the bottom of the holder and is so constructed as to be under tension tending to draw the carbid-holder 80 toward the conical flange. When this is done the flexible connection D between the base of the lamp and the carbid-holder is compressed and the storage capacity for the gas is reduced. This at the same time causes the valve to be lifted from its seat and a portion of carbid to be discharged into the water. This 85 will cause the generation of gas, which will raise the carbid-holder and close the valve. 90

The carbid-holder is movably secured to the base by means of rods H, which are secured to the flange C and extend upwardly into tubes H' within the carbid-holder. This permits the carbid-holder to rise and fall, while 100

holding it in otherwise fixed position to the base. The gas is taken from the gas-receiving chambers through a hole I^2 , which leads into a drying-chamber I . Within this drying-chamber is placed absorbent cotton or any other suitable drying material which will extract the moisture therefrom. To this drying-chamber is connected a pipe J , leading to a burner J' , which, as herein shown, lies within a reflector-cone K .

The construction shown in Fig. 5 is substantially that of Fig. 1 just described. The material difference is that the drying-chamber I is connected with the interior of the lamp by means of a pipe J^2 . The position or location of the burner is not an essential feature. In using the device as a bicycle-lantern the burner would be located as shown. In using the device as a house-lamp the burner would probably be otherwise located. As shown in Fig. 5, the pipe J , leading to the burner, is provided with a stop cock or valve J^3 . The conical flange C prevents the water contained in the lower portion of the lantern from being thrown upward, so as to moisten the carbid. In use upon bicycles the lantern is apt to be considerably shaken at times. This will throw the water about somewhat. The water being thrown against the sides of its containing-chamber will be deflected upward until it comes in contact with the conical flange C . This flange will then deflect the water downward and prevent any possibility of its getting into the upper part of the lantern.

The use of the flexible connection between the carbid-holder and the base, thus forming a bellows or accordion connection, provides for the expansion and contraction of the gas-containing chambers without necessitating a liquid seal. This is a matter of considerable importance for bicycle-lanterns, as a liquid seal would be very hard to maintain.

The lantern as herein shown and described is very simple and cheap in its construction, while being at the same time convenient and not likely to get out of order.

Having thus described my invention, I claim as new and desire to secure by Letters Patent—

1. An acetylene-gas generator consisting of two main parts, the lower one of which forms the water-reservoir and the upper one of which forms the carbid-holder, and a flexible-fabric connection between the sides of the two, forming an expansive gas-chamber.

2. An acetylene-gas generator, comprising a water-reservoir in the base, a carbid-holder in the top, a flexible-fabric connection between the two, forming an expansive gas-chamber, and a tension-spring between the water-reservoir and carbid-holder acting to compress or reduce the gas-chamber.

3. An acetylene-gas generator having a water-reservoir in the base, a carbid-holder in

the top, a flexible-fabric connection between the two, forming an expansive gas-chamber, a spring acting to compress or reduce the gas-chamber, and means by which the compression of the gas-chamber causes the feeding of a fresh supply of carbid.

4. An acetylene-gas generator having a water-reservoir in its base, a carbid-holder in its top, a valve in the latter adapted to discharge the carbid into the water, and an annular conical flange in the water-reservoir above the water-level and projecting downwardly, whereby splashing of water upon the carbid-holder or the feeding mechanism is prevented.

5. In an acetylene-gas generator having a carbid-holding and feeding mechanism located in the top of the water-reservoir, a protector consisting of a conical flange attached to the side walls of the water-reservoir and extending downwardly, the point of the cone being open and the whole being above the water.

6. An acetylene-gas generator having a water-reservoir in its base, a carbid-holder in its top, a flexible-fabric connection between the two forming an expansive and compressible gas-chamber, a spring acting to compress this chamber, and a valve in the bottom of the carbid-holder adapted to be engaged and raised by the compression of the gas-chamber and thus to furnish a new charge of carbid.

7. An acetylene-gas generator having a water-reservoir in its base, a carbid-holder in its top, a flexible-fabric connection between the two, forming an expansive and compressible gas-chamber, a spring acting to compress this chamber, a valve in the bottom of the carbid-holder adapted to be engaged and raised by the compression of the gas-chamber and thus to furnish a new charge of carbid, and a spring of less force than the other spring acting upon said valve, to close it.

8. An acetylene-gas generator having a water-reservoir in its base, a carbid-holder in its top, a flexible-fabric connection between the two, forming an expansive and compressible gas-chamber, a spring acting to compress this chamber, a valve in the bottom of the carbid-holder adapted to be engaged and raised by the compression of the gas-chamber and thus to furnish a new charge of carbid, and an adjustable rod passing into the carbid-holder and adapted to be engaged with the valve, to lock it.

9. An acetylene-gas generator having a water-reservoir in its base, a carbid-holder in its top, a flexible-fabric connection between the two, forming an expansive and compressible gas-chamber, guides connecting the carbid-holder and water-reservoir, a spring acting to compress the gas-chamber, a valve in the bottom of the carbid-holder adapted to be engaged and raised by the compression of the gas chamber and thus to furnish a new

charge of carbid, and a spring of less force than the other spring and acting upon said valve to close it.

10. An acetylene-gas generator constructed in sections separated one from the other and one of which forms the water-reservoir and the other the carbid-holder, and a flexible-

fabric connection between the two forming an expansive gas-chamber.
